CLAIM

The ornamental design for a combination cushion frame and rigidizer arms for respiratory mask, as shown and described.

DESCRIPTION

FIG. 1 is a front perspective view of a combination cushion frame and rigidizer arms for respiratory mask showing a first embodiment of our new design;

FIG. 2 is a front view thereof;

FIG. 3 is a rear view thereof;

FIG. 4 is a top view thereof;

FIG. 5 is a bottom view thereof;

FIG. 6 is a left side view thereof;

FIG. 7 is a right side view thereof;

FIG. 8 is a front perspective view of a combination cushion frame and rigidizer arms for respiratory mask showing a second embodiment of our new design;

FIG. 9 is a front view thereof;

FIG. 10 is a rear view thereof;

FIG. 11 is a top view thereof;

FIG. 12 is a bottom view thereof;

FIG. 13 is a left side view thereof; and,

FIG. 14 is a right side view thereof.

The broken lines in the drawings depict portions of the combination cushion frame and rigidizer arms for respiratory mask that form no part of the claimed design.

1 Claim, 10 Drawing Sheets
